CLAIM

I claim the ornamental design for a utility cutter, as shown and described.

DESCRIPTION

FIG. 1 is a top, left side perspective view of a utility cutter, showing the new design;

FIG. 2 is a bottom, right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side view thereof; and,

FIG. 8 is a right side view thereof.

The shading lines shown in the drawings represent the approximate three-dimensional contour of the design, and are not intended to indicate surface decoration.

The broken line(s) shown in the drawings illustrate portions of the utility cutter that form no part of the claimed design.
